CLAIM

The ornamental design for an internal combustion engine, as shown.

DESCRIPTION

FIG. 1 is a front perspective of an internal combustion engine showing our new design;

FIG. 2 is a top plan view thereof, the bottom plan view being plain and unornamented;

FIG. 3 is a left side elevational view thereof;

FIG. 4 is a front elevational view thereof;

FIG. 5 is a right side elevational view thereof; and,

FIG. 6 is a rear elevational view thereof.
